EXERCISER

Robert M. Martin, 90 N. Hudson,
Pasadena, Calif. 91101

Filed Sept. 3, 1971, Ser. No. 177,924

Term of patent 14 years

Int. Cl. D21—02

U.S. Cl. D34—5 K

Fig. 1

Fig. 2

Fig. 3

Fig. 4

Fig. 5

Fig. 6

FIG. 1 is a perspective view of an exerciser showing my new design;

FIG. 2 is a top plan view thereof;

FIG. 3 is a bottom plan view thereof;

FIG. 4 is an end elevational view as seen from the left hand end of FIG. 2;

FIG. 5 is an end elevational view as seen from the right hand end of FIG. 2; and

FIG. 6 is a typical side elevational view thereof.

I claim:

The ornamental design for an exerciser, substantially as shown and described.
